UNITED STATES PATENT OFFICE.

PETER A. SOLEM, OF CINCINNATI, OHIO, ASSIGNOR TO J. A. FAY & EGAN COMPANY, OF CINCINNATI, OHIO, A CORPORATION OF WEST VIRGINIA.

PLANING MACHINERY.

1,186,048.

Specification of Letters Patent. Patented June 6, 1916.

Application filed February 3, 1913. Serial No. 745,925.

To all whom it may concern:

Be it known that I, PETER A. SOLEM, a citizen of the United States, residing at Cincinnati, in the county of Hamilton and 5 State of Ohio, have invented certain new and useful Improvements in Planing Machinery, of which the following is a specification.

My invention relates to wood planing machinery employing a side-head or heads, of which so-called planing and matching machines, flooring machines, and molding machines may be instanced as examples.

It is the object of my invention to provide 15 novel means for mounting the upright shaft to which the side cutter-head is secured; further to provide novel means for adjusting the side-head or heads vertically; further to provide novel means for supporting 20 the side-head hanger or hangers; further to provide novel clamping means for the same; and further to provide novel contact-means for the stock.

It is the object of my invention further 25 to provide a novel construction and mounting for the side-head hanger or hangers whereby ready removal of the shaft-bearing parts is accomplished; further to provide novel adjusting and clamping mechanism 30 for the side-head hangers whereby either or both of said hangers may be adjusted or clamped from the outside of the machine; further to provide novel means for supporting 35 the upright cutter-head shaft and adjusting the same; further to provide novel clamping means for releasing or clamping either side-head hanger independently of the other side-head hanger from the outside of the machine-frame; and the invention 40 will be further readily understood from the following description and claims, and from the drawings, in which latter:—

Figure 1 is a front end elevation of my improved device, the frame of the machine 45 being shown in cross-section. Fig. 2 is a side elevation of the same. Fig. 3 is a side elevation of the right-hand hanger and its attendant parts, the parts between the hangers being shown in section on the line 3—3 50 of Fig. 1. Fig. 4 is a plan view of my improved device. Fig. 5 is a vertical axial section taken on the axial line of the cutter-head shaft of the left-hand hanger, on the line 5—5 of Fig. 1. Fig. 6 is a horizontal 55 cross-sectional bottom view of my improved

device, taken on a line corresponding to the line 6—6 of Fig. 1. Fig. 7 is a cross-section on the line 7 of Fig. 3, showing the clamping means for the side-head hangers and the upper and lower stock-positioning 60 means. Fig. 8 is a detail in section on the line 8—8 of Fig. 2 showing the means for end-positioning the clamp-shafts; and, Fig. 9 is a detail in section on the line 9—9 of Fig. 4, showing the adjusting means for the stationary chip-breaker and the means for securing the matcher-leg to the matcher-plate.

I have shown only so much of a wood planing machine as is necessary to illustrate 70 my invention, it being understood that the machine may be provided with a horizontal cutter-head or cutter-heads operating upon either or both the top or bottom face of the stock and with suitable feeding mechanism, such as power driven feed-rolls, for feeding the boards or stock past the cutter-heads.

11 represents the main frame of the machine, which is arranged to support the 80 horizontal cutter-head or heads and the feeding devices in suitable manner, and which may also contain a table 12 on which the stock is arranged to be fed in the machine in the direction of the arrow *a*. 85

Side-head hangers 13, 14, also known as matcher-hangers are mounted in the machine. I shall designate the left side-head hanger as 13 and the right side-head hanger as 14, either one or both of which may be 90 employed. These side-head hangers are to a great extent duplicates of each other and in describing the parts of one which are duplicated in the other, I shall refer to the duplicated parts by similar but primed reference numerals, the description referring primarily to the left-hand hanger.

The side-head hanger, as shown, comprises a plate 15, hereinafter also termed a matcher-plate, a leg 16, and a bearing-yoke 100 17. The plate is slidable laterally between guides 18, 19, rigid on the main frame, and shown on cross-girts of the same. (See Figs. 2, 3, 4 and 5.) The guide 18 is shown as a dovetail guide with which a guideway 20 on the plate 15 cooperates. The guideway 20 comprises closely adjacent front and rear walls for forming a narrow and long guideway which will prevent binding and torsional strain between the guideway and 110

guide for preventing swiveling of the plate and for maintaining the plate parallel with the guide during the adjustments thereof and causing the plate to move in true lines with relation to the guide. The front wall of the guideway is shown formed by a strip 21 secured to the plate. (See Fig. 1.) The guide 19 is shown as a flat guide, with which a guideway 22 on the plate co-operates. The guideways extend preferably across the width of the plate.

25 is a clamp-shoe arranged to clamp the plate in adjusted positions. (See Figs. 2, 3, 5, 6 and 7.) It has a clamping face 26 which coacts with the cross-girt on which the guideway 22 is located. The clamp-shoe preferably extends a substantial distance across the width of the plate. A clamp-screw 27 is threaded into a threaded bearing 28 in the plate and journaled in a bearing 29 in the clamp-shoe. A spiral-gear 30 is secured to the clamp-screw, the clamp-shoe being received between said spiral gear and the plate for being clamped therebetween, the clamp-shoe having a ridge 31 thereon which impinges the plate.

The clamping face of the clamp-shoe is preferably interrupted at the screw position, see the interruption 32', Fig. 7, so that 30 clamping effect is insured at points distanced from said screw toward the ends of the plate, for distributing the clamping effect over a larger area. In this manner, further, three clamping points are provided 35 for the clamp-shoe, namely, the ridge and the clamping faces adjacent the respective ends of the clamp-shoe.

Each of the side-head hangers is provided 40 with a clamp and each of the clamps is independently operable, preferably from the outside of the machine, so as to independently clamp the side-head hangers rigidly in the machine in order that either side-head hanger may be adjusted independently 45 of the other and clamped without affecting the adjustment or clamped relation of the other. By providing these independent clamps I avoid a disarrangement of adjustment which would otherwise result from 50 mere unclamping of a side-head hanger and reclamping of the side-head hanger without adjustment of the same. The clamping is effected by a clamping force exerted in a direction at substantial right angles to the 55 plane of the guiding face, so as to reduce the tendency of disarrangement of adjustment to the minimum, the guiding and clamping being effected preferably at opposite sides of the cross-girt.

60 For operating the clamps, shafts 35, 35', are provided, with which spiral gears 36, 36', have spline-connection, as shown at 37, 37', the said spiral gears having hubs between bearings 39, 39', in depending lugs 65 40, 40', depending from the plates 15, 15',

the said shafts being journaled in said bearings. The spiral gears 36, 36', mesh with the spiral gears 30, 30'. The clamp-shoes are guided by said lugs to prevent swiveling motion of the shoes. The shafts 35, 35', are 70 journaled in bearings 41, 41', (see Figs. 2 and 8), in the side of the main frame and have means thereon for turning the same, shown by the squared ends 42, 42', arranged to receive a suitable crank-arm 46 for turning the shafts. The shafts are positioned longitudinally by collars 43, 43', thereon, received in said bearings, the outer parts of 75 said bearings being formed in an outer cap 44 releasably secured to the frame by a bolt 80 45.

The leg 16 of the side-head hanger is releasably secured to the plate 15 by bolts 47, and has a positioning connection 48, shown as a tongue and groove connection, for positioning the depending leg in line with the guideways of the plate. (See Figs. 4 and 9.) The bearing-yoke 17 is adjustably mounted 85 on the leg and has bearings 49, 50, thereon in separated relation for an upright shaft 51, to which a side-head 52 is suitably releasably secured, and having an operating pulley 53 90 between the bearings.

56 is a guide for the lower end of the legs, this guide extending crosswise of the machine, the legs being provided with coacting guideways 57, 57', one of the walls whereof is formed by a clip 58 releasably secured to the leg by bolts 59. The guide 56 is releasably secured to the main frame by 100 bolts 60.

For moving the side-head hangers laterally on their guides I provide adjusting screws 61, 61'. (See Figs. 1, 2, 5 and 6.) The adjusting screw 61 has threaded connection in a bearing 62 in the leg 16 and the adjusting screw 61' has threaded connection in a bearing 62' on the leg 16'. Upon lateral adjustment of either or both the side-head hangers, the same are clamped in place by 105 means of the clamp-shoes 25, 25', in the manner hereinbefore stated. The adjusting screws 61, 61' are longitudinally positioned by collars 63, 63' thereon, received in bearings 64, 64', whose outer ends are formed 110 by a cap 65 secured in place by a bolt 66, similar to the end-positioning means of the shafts 35, 35'. The outer ends of the adjusting screws are provided with turning means, shown as squared ends 67, 67', arranged to receive a suitable socket-crank, 115 similar to the part 46.

The manner of supporting the side-head hangers by supporting the plates of the same at front and rear in guideways and providing a guideway at the front of the lower end of the same, provides a three-point support for each of the side-head hangers, the principal support being obtained from the front and rear guides at the top of the same, the 120 125 130

guide at the bottom being a steadyng support. The manner of clamping the side-head hangers in place after adjustment permits the clamping action to take place with 5 minimum disarrangement of the adjusted positions of the side-head hanger.

The bearing-yoke is adjustable up and down on the depending leg, the leg being provided with a guideway 70 in which a 10 guide 71 on the bearing-yoke has sliding movement. (See Figs. 1, 2, 5 and 6.)

72 is a screw-rod journaled in a bearing 73 on the leg and having threaded connection in a bearing 74 on the bearing-yoke. 15 A spiral gear 75 is secured to the screw-rod, a collar 76 preventing endwise movement of the screw-rod in its bearing 73. A spiral gear 77 has a hub 78 journaled in a bearing 79 on the leg and meshes with the spiral 20 gear 75 for operating the same. A collar 80 on the hub prevents endwise movement of the hub. Operating shafts 84, 84', are provided for the spiral gears 77, 77'. These 25 respectively have spline-connections 85, 85', with said spiral gears. The shaft 84' also passes through an opening 86 in the leg 16, and an opening 86' in the leg 16' provides clearance for the shaft 84.

The operating shafts 84, 84', are journaled 30 in bearings 87, 87', and at their outer ends are provided with operating means 90, 90', shown as squared ends of said shafts, adapted to receive a usual crank-handle for turning the same, similar to the part 46. These 35 operating shafts are located in endwise positions by means of collars 91, 91', in said bearings, the outer portions of said bearings being in a cap 92 releasably secured to the main frame by a bolt 93. Upon removal of 40 the cap the operating shafts may be removed endwise from the machine.

96, 96' are shaving-hoods received about the cutter-heads, the shaving-hood 96 being releasably pivoted on a pin 97 secured on the 45 plate 15, this shaving-hood having a chip-breaker 98 thereon adjustably secured thereto, the stem 99 thereof being slidale in a socket 100 of the shaving-hood and secured in place by a set-screw 101. The shaving-hood 96' is releasably secured to the plate 50 15' by bolts 102. The swinging shaving-chute and chip-breaker are held against the stock by means of a weight 103 secured to the swinging shaving-chute at 104 by means 55 of a flexible connection 105 passing over pulleys 106, 107.

110 is a hold-down bar adjustable up and down on a standard 111 on the plate by means of an adjusting screw 112 journaled on the 60 hold-down bar in a bearing 113 and threaded into a bearing 114 on the standard, there being a guiding connection 115 between the hold-down bar and standard. A bolt 116 threaded into the hold-down bar and received through a slot 117 in the standard

rigidly secures the parts in adjusted relations.

The standard is adjustable crosswise of the plate, having guiding connection 118 therewith, being adjusted by means of an 70 adjusting screw 119 journaled in a bearing 120 on the plate and threaded into a threaded bearing 121 of the standard, a bolt 122 being received through a slot 123 in the base of the standard and threaded into the plate 75 for securing the parts in adjusted relations. The lower portion of the inside face of the standard acts as a side-guide for the stock. The hold-down face 124 of the hold-down bar is located between the upper guides of 80 the hanger, the adjusting means therefor being located substantially above one of said guides.

I prefer to provide a lower bridge-piece 126 coöperating with the hold-down bar. 85 This bridge-piece is arranged to support the lateral edge of the stock while passing the side cutter-head, and will be described with particular reference to the right-hand hanger. (See Figs. 3, 6 and 7.) The bridge-piece is adjustable up and down on an apron 127' depending from the plate 15' and clamped in place by means of bolts 128' received through slots 129' and threaded into said apron, the adjustment being effected by 90 means of a set-screw 130' threaded into a bearing 131' at the lower end of said apron and locked in place by a lock-nut 132' and bridge-piece being supported between the front and rear guides of the matcher-plate, 100 and received in a recess 133 at the inner edge of the matcher-plate. The standard 111 has a recess 134 for accommodating the support. This adjustment raises and lowers the bridge-piece with relation to the stock-supporting face of the table, which is important especially where a formed cutter, such as a tongue or groove cutter, is being employed on the side cutter-head, and further permits the taking up of wear which may be occasioned by the passing of stock over the stock-supporting face of said bridge-piece. Locating said hold-down bar and the bridge-piece between front and rear guides at the 105 top of the hanger affords an especially rigid construction in which vibrations are reduced to the minimum, and is especially valuable in high-speed machines.

The stock is arranged to be fed against a side-guide 136, whose guiding face is in line 120 with the guiding face at the lower end of the standard 111. This side-guide is adjustable laterally. There is a stationarily positioned chip-breaker 137 at the feed-in side of the right-hand cutter-head adjustable toward 125 and from the cutter-head in lines parallel to and at right angles to the lines of feed of the stock. It is preferably mounted on a support 138 which may be part of the side-guide having connection therewith by 130

4
a web 139. Lateral adjustment is provided by means of a set-screw 140 bearing against said support and having threaded connection in a lug 141 on the plate, a bolt 142 passing through a slot 143 in said support and threaded into the shelf for clamping the support in place. The chip-breaker 137 has a guideway 144 coöperating with the guide 145 on said support for adjusting the chip-breaker parallel to the line of feed of the stock, a bolt 146 passing through a slot 147 in the chip-breaker and threaded in a threaded bearing in said support, clamping the parts in place. By these means a laterally adjustable side-guide is provided above each top guide of the hanger, respectively at front and rear of the cutter-head, a coöperating edge support and hold-down, having up and down adjustment, being located between said side-guides and said top hanger-guides.

My improved device provides ready means for removing the bearing-portions of the side-head shafts and for readily replacing the same in correct positions. This is accomplished by removal of the caps 65 and 92, whereby the adjusting shafts may be turned and moved longitudinally for disconnection with the legs. The bolts 59 and 30 clips 58 are removed, whereupon the lower ends of the legs may be swung forwardly and the legs and bearing-yokes thereon removed through the bottom of the machine.

Having thus fully described my invention, 35 what I claim as new and desire to secure by Letters Patent, is:

1. In a planing machine, the combination of a side-head hanger and a three-point laterally extending guiding suspension therefor, the guiding points whereof are located respectively at the top-front, the top-rear and the bottom-front portions of said hanger, said guiding suspension at said top-front of said hanger comprising closely adjacent plane walls extending up and down and laterally parallel for preventing swiveling of said hanger, and clamping means for said hanger at the top-rear portion of said hanger.

2. In a planing machine, the combination of a side-head hanger and laterally extending guiding supports therefor respectively at the front and rear of the top of said hanger, one of said guiding supports comprising closely adjacent plane laterally parallel guiding walls extending up and down, the other of said guiding supports having a substantially horizontal guiding face, means for laterally shifting said hanger lengthwise of said guiding supports, and a clamp for clamping said hanger in adjusted positions comprising a clamp-shoe, said clamp-shoe having a clamping face which has an interruption therein for forming separated plane clamping faces parallel with

said substantially horizontal guiding face, and a clamp-screw for said shoe at said interruption clampingly acting perpendicular to said substantially horizontal guiding face.

3. In a planing machine, the combination 70 of a side-head hanger, laterally extending guiding means therefor, means for adjusting said hanger laterally along said guiding means, said side-head hanger having a flat guiding wall and clamping means for said 75 hanger comprising a ledge, a clamp-shoe, a clamp-screw for the latter, said clamp-shoe provided with a stiffening and guiding clamp-ridge at one side of said clamp-screw coöperating with said guiding wall of said 80 hanger and with a clamping face at the other side of said clamp-screw, said clamping face coöperating with said ledge and having an interruption therein adjacent to said clamp-screw.

4. In a planing machine, the combination 85 of a side-head hanger comprising a supporting plate, a leg releasably secured thereto and depending therefrom, a bearing-yoke, an upright side-head spindle, said bearing-yoke comprising upper and lower bearings 90 for said spindle, means for adjusting said bearing-yoke up and down on said leg for adjusting said bearing-yoke, bearings and spindle simultaneously up and down on said 95 leg, and laterally extending guiding means on which said plate is laterally adjusted, and constructed and arranged for simultaneous removal of said leg, bearing-yoke, bearings and spindle during maintenance of guiding 100 relation between said plate and guiding means.

5. In a planing machine, the combination 105 of a frame, separated laterally extending guides therein, a side-head hanger with the upper portion of which each of said guides has guiding connection, a lower support for the edge of stock, and adjusting means located between said guides for adjusting said support up and down on said hanger.

6. In a planing machine, the combination 110 of a frame, separated laterally extending guides therein, a side-head hanger comprising a supporting plate having guiding connections with said guides and a spindle-supporting leg depending from said plate, said plate having a depending apron at the side portion thereof located between said guides, and a support for the edge of stock adjustable up and down on said apron.

7. In a planing machine, the combination 115 of a frame having separated laterally extending guides therein, a side-head hanger comprising a plate, a depending leg releasably secured to said plate, and bearings supported by said leg, an upright cutter-head spindle journaled in said bearings, said plate having guiding connections with said guides, a lower support for the edge of stock, adjusting means between said support and 120

125

130

135

plate located between said guides, and constructed and arranged for removal of said leg during maintenance of adjusted position of said lower support.

- 5 8. In a planing machine, the combination of a frame, separated laterally extending guides therein, a side-head hanger with the upper portion of which said guides have guiding connections, said side-head hanger 10 comprising a plate and a depending cutter-head spindle-supporting leg releasably secured to said plate, a laterally adjustable

side-guide for the stock above each of said laterally extending guides, and a vertically adjustable bridge-support for the edge of 15 stock extending between said side-guides and between said laterally extending guides.

In testimony whereof, I have hereunto signed my name in the presence of two subscribing witnesses.

PETER A. SOLEM.
